EQUIPMENT FOR TESTING TROLLEY WIRE
INSULATORS AND RAIL BONDS OF ELEC-
TRIC RAILWAYSAndrew J. Sorensen, Edgewood, Pa., assignor to
The Union Switch & Signal Company, Swiss-
vale, Pa., a corporation of Pennsylvania

Application July 23, 1947, Serial No. 762,850

2 Claims. (Cl. 175—183)

1

My invention relates to equipment for testing trolley wire insulators and rail bonds of electric railways, and more particularly to such testing equipment for electric railways in mines.

In mines an electric railway for hauling out the coal or ore generally uses a trolley wire suspended from the roof of the mine by hangers which are spaced at frequent intervals and each of which includes an insulator. The propulsion current circuit comprises the trolley wire and the bonded rails and generally uses direct current of 200 to 600 volts. The roof of the mine comprises earth, rock and other material and a faulty insulator of a hanger may result in the full voltage of the propulsion current being impressed between the trolley wire and ground with the result a relatively large current may flow from the trolley wire into the roof and from there through the ground path to the return rail system. The heat developed at a faulty hanger due to this relatively large current flowing to ground can be intense enough to start a fire because of the combustible material that usually accumulates about the roof of a mine. Such fire tends to cause explosion and other danger to the miners. Furthermore, the leakage is a loss of power and when a number of hangers become faulty, the leakage current may be large enough to impair the operation of the railway.

Again, a broken or defective rail bond tends to materially increase the resistance of the propulsion current circuit and to unbalance the distribution of the propulsion current in the rails. A number of broken and defective rail bonds may so increase the resistance of the rail return as to reduce the voltage available for the locomotive motors to a point where the loss of power materially affects the operation of the locomotive. The rail bonds of a mine track are subjected to a great deal of strain due to the fact that the roadbed of any mine track is not as a rule in very good condition.

It is therefore in the interest of safety and economy that tests of the trolley wire insulators and the rail bonds be made frequently, and such testing of the trolley wire insulators and rail bonds in a mine track is laborious and an expensive item in the maintenance.

Accordingly, a feature of my invention is the provision of novel and useful test equipment for detecting faulty trolley wire insulators and rail bonds of electric railways.

Another feature of my invention is the provision of improved test equipment capable of being mounted upon a mine locomotive or other vehicle

2

for automatically detecting faulty trolley wire hangers and rail bonds as the vehicle moves over the mine track.

Other features, objects and advantages of my invention will appear as the specification progresses.

To attain the foregoing features, objects and advantages of my invention, I provide on a locomotive or other vehicle of an electric railway, 10 a source of alternating current, one terminal of which source is preferably connected to the trolley wire through a trolley wheel and the other terminal of which source is connected to the rails through the frame and wheels of the locomotive or vehicle. In this way, the alternating current is applied to the circuit network which includes the trolley wire and the rails. The alternating current to be used is preferably of a relatively high frequency, such as, for example, 10,000 cycles per second or higher, and current of an effective value flows in the trolley wire from the point at which it is applied thereto and returns through the two rails in multiple due to the distributed capacitance of the trolley wire and the rails.

Two receiving circuits are mounted on the vehicle for inductively receiving energy from the trolley wire. These two receiving circuits are preferably alike and include pick-up coils which are symmetrically spaced in a common plane relatively close to the trolley wire to have substantially the same inductive relationship to the trolley wire. These two receiving circuits are balanced in such a way that the electromotive forces induced in the two pick-up coils are equal and balance out when the same value of alternating current flows in the trolley wire past each pick-up coil. However, the electromotive forces are unequal, and an electromotive force equal to the difference of the two appears when the receiving coils are spaced on opposite sides of a hanger having a faulty insulator. This is so because a portion of the alternating current flows through the broken down insulator into the roof of the mine, and more current flows past one coil than the other. This unbalanced condition of the two receiving circuits causes the operation of an indicator to indicate the presence of the broken down insulator.

Two other receiving circuits are provided on the locomotive or vehicle for detecting faulty rail bonds. These two receiving circuits include two pick-up coils, one for each circuit and which coils are mounted one over each rail. These two receiving circuits are arranged in such a way

that when approximately the same electromotive forces are induced in the pick-up coils due to approximately equal values of the alternating testing current flowing in the two rails, the two electromotive forces cancel, but that when a rail joint having a broken bond passes under one or the other of the pick-up coils and the testing currents are unequal the unequal electromotive forces induced in the pick-up coils no longer cancel, and the unbalanced portion of the electromotive forces is applied to an indicator to indicate the presence of the faulty rail bond.

These two indicating devices may be independent, but I prefer to use an indicator in the form of a twin electron ray tube so that the operator needs but look at the one indicating element to observe the two indications as the locomotive moves through the mine, one shadow angle of the electron ray tube indicating faulty insulators and the other shadow angle of the tube indicating faulty rail bonds.

For a fuller understanding of my invention, reference may be had to the accompanying drawings and the accompanying description thereof, Fig. 1 of the drawings being a diagrammatic view showing one form of the test equipment embodying my invention when mounted on a locomotive of an electric mine railway, and Fig. 2 being a diagrammatic view showing another form of the apparatus for detecting faulty rail bonds, and which apparatus can be used for the corresponding portion of the equipment of Fig. 1.

In each of the two views, like reference characters are used to designate similar parts.

It is to be understood that the invention is not limited to a mine railway, and this one application of the equipment serves to illustrate the many places the equipment is useful.

Referring to Fig. 1, the reference character MT designates the track of an electric railway of a mine, the two rails 1a and 1b of the track being shown in section at the right-hand end of the drawing for reasons that will become apparent hereinafter. The reference character TW designates a trolley wire of the electric railway. This trolley wire TW is suspended by hangers HA spaced at frequent intervals, there being three such hangers illustrated in the drawing. In the usual arrangement each hanger HA is secured to the roof of the mine by suitable fasteners secured in the rocks and earth forming the roof. These hangers may be of any standard and suitable form, and each includes an insulator 10, so that the trolley wire TW is normally insulated from the mine roof, that is, it is normally insulated from ground.

A propulsion power source, usually in the form of a direct current generator, not shown, has one terminal connected to the trolley wire TW and its other terminal connected to the two rails 1a and 1b, the rails being bonded in the usual manner to complete the return circuit path for the propulsion current. To aid in the understanding of the invention, I shall assume that the propulsion current is a direct current of 250 volts, but other currents and voltages can be used. It is clear that as long as the insulator 10 of each hanger HA is intact, little or no propulsion current leaks from the trolley wire to ground through the mine roof, but that if one of the insulators 10 becomes short circuited substantially, the full voltage of the propulsion current source is impressed between the trolley wire TW and ground and a relatively large current leaks through the mine roof. As stated hereinbefore,

the heat created around a faulty hanger due to this leakage current may be so intense as to cause a fire since the mine roof includes much dust and combustable material. Such a fire may readily become the cause of an explosion and endanger the miners' lives. Also, the leakage current is a loss of power and several faulty insulators existing at the same time may cause the loss of power to become so great as to overload the generator to the extent that the operation of the mine railway is seriously impaired.

Furthermore, it is clear that if the bonding of the rails 1a and 1b is in good condition, the propulsion current will divide approximately equally in the two rails, and a minimum resistance in the rail return path is present but that a broken bond in one rail will tend to unbalance the distribution of the propulsion current in the rails, and also to introduce an abnormal resistance in the rail circuit. To detect the presence of such faulty insulator and rail bond, test equipment is mounted upon a locomotive LO of the railway, and which locomotive is normally provided with a trolley pole TP for collecting propulsion current from the trolley wire for operating the motors of the locomotive, the motors being omitted from the drawing since they are not required for a full understanding of the present invention.

The locomotive LO is provided with a source of periodic or alternating current, such source being indicated conventionally at OS. This source OS may be any one of several forms and may be an electron tube oscillator. By way of illustration, I shall assume that the source OS supplies a current of the frequency of the order of, say, 10,000 cycles per second, but other frequencies can be used. The output of the oscillator OS is supplied to a primary winding 11 of a transformer T1, a secondary winding 12 of which has one terminal connected to the trolley pole TP through a capacitor 13 and a conductor 14 and its other terminal connected to the rails 1a and 1b through a conductor 15 connected to the frame and wheels of the locomotive. Thus the alternating current supplied by the oscillator OS is applied between the trolley wire TW and the rails and will cause current to flow in the trolley wires out from the locomotive and return through the track rails in multiple due to the distributed capacitance of the trolley wire and rails.

To aid the flow of the carrier or high frequency alternating current, a temporary connection including a capacitor 16 may be connected between the trolley wire and the track rails, but ordinarily such temporary connection would not be required.

A receiving unit RU is provided for the locomotive LO. The unit RU is adaptable of being carried on an auxiliary trolley pole ATP mounted on the locomotive with two swivel joints 17 and 18 so that the unit RU mounted on the upper joint 18 will always ride on the trolley wire in the same position. The unit RU is formed with a housing or case 9 of suitable insulating material to protect the enclosed elements, to be shortly referred to, from weather and from the propulsion current. Preferably, at least two wheels 20 and 21 are journaled in the housing 9 to follow the trolley wire and assure that the unit RU always has a definite position with respect to the trolley wire. Two pick-up coils 22 and 23 are mounted in the case 9. These two pick-up coils 22 and 23 are preferably alike and are symmetrically spaced so that the two coils will have

substantially the same inductive relationship to the trolley wire, the two coils being spaced a given distance apart along the trolley wire. Capacitors 24 and 25 are connected across the pick-up coils 22 and 23, respectively, to tune the coils to the frequency of the alternating current supplied by the oscillator OS and to suppress voltages induced in the coils due to noise and other energy flowing in the trolley wire.

The two pick-up coils 22 and 23 are connected one to each of two receiving circuits, the circuit for the coil 22 including the top terminal of the coil, wire 26, left-hand portion of a resistor R1 as viewed in Fig. 1, to an intermediate adjustable terminal 27, a tuning coil 28, wires 29 and 30, and the lower terminal of the pick-up coil 22, and the circuit for the pick-up coil 23 including top terminal of the coil, wire 31, right-hand portion of resistor R1 to intermediate terminal 27, tuning coil 28, wires 29 and 32, and the lower terminal of the coil. The pick-up coils 22 and 23 are disposed and wound so that when an alternating current flows in the trolley wire TW the electromotive forces induced in the coils cause at a given instance the top terminal of coil 22 and the lower terminal of coil 23, as viewed in the drawing, to be positive, and at the next instant the lower terminal of coil 22 and the top terminal of coil 23 to be positive. It follows that the currents tending to flow in the tuning coil 28 due to the electromotive forces induced in the coils 22 and 23 oppose each other and will balance out when the same value of alternating current flows in the trolley wire past each of the pick-up coils. The tuning coil 28 is provided with an adjustable magnetic core or otherwise made adjustable to tune the two receiving circuits to resonance at the frequency of the test current. The adjustable terminal 27 of resistor R1 aids in the balancing of the two receiving circuits. A capacitor 33 is also connected across the tuning coil 28 to aid in the tuning and to bypass currents in the receiving circuits due to frequencies other than that derived from the source OS.

The test equipment of the locomotive LO includes an indicator which is disclosed as a twin electron ray tube ET of the indirectly heated type. The tube ET is provided with a cathode 34, two control electrodes or grids 35 and 36, an anode 37, and a target electrode 38. The tube ET is powered from a source on the locomotive, not shown, but having positive and negative terminals indicated at B100 and N100, respectively. The anode 37 and the target electrode 38 are connected to the positive terminal B100 of the power source in the usual manner, resistors R4 and R5 being interposed in the connection in the customary arrangement. Cathode 34 is connected to the negative terminal N100 of the source to complete the usual anode circuit. Control grid 35 and cathode 34 are connected across the tuning coil 28 and capacitor 33. Consequently, when a zero voltage exists across the tuning coil 28 no control voltage is applied to the control electrode 35 of the tube, and substantially no shadow angle of the corresponding section of the tube ET is created. Thus when the locomotive LO is moving along a stretch of the railway track, and the insulators 10 of the different hangers are all in good condition, equal electromotive forces are induced in the pick-up coils 22 and 23, these two electromotive forces cancel each other in the two receiving circuits so that zero voltage exists across the tuning coil 28, and substantially no shadow angle is indicated for the corresponding

section of the indicator tube ET. Assuming that, as the locomotive LO moves along the track, a hanger, such as the center hanger shown in Fig. 1, comes between the two pick-up coils 22 and 23, and in which hanger the insulator 10 is short circuited, a relatively large portion of the alternating current supplied by the source OS will leak to ground through the faulty insulator with the result that the current flowing in the trolley wire past pick-up coil 22 is larger than the current flowing in the trolley wire at pick-up coil 23. This causes the electromotive force induced in coil 22 to be larger than that induced in coil 23, and a voltage equal to the difference of these two electromotive forces appears across the tuning coil 28 and is applied to the control electrode 35 of tube ET causing the display of a corresponding shadow angle for the corresponding section of the electron ray tube ET. Thus the operator of the locomotive LO having the tube ET mounted visually before him is informed whenever the locomotive passes under a hanger having a broken down insulator.

To detect broken rail joint bonds, the locomotive LO is provided with two pick-up coils 40 and 41 mounted on the locomotive for inductive relation with the rails 1a and 1b, respectively, as clearly indicated in the right-hand portion of Fig. 1. Coils 40 and 41 are preferably alike and are disposed to have like inductive relationship with the respective rails. That is, the alternating current flowing in the rails in multiple with an equal value of current in each rail will induce electromotive forces of equal value in the two pick-up coils 40 and 41. Each coil 40 and 41 is connected to a receiving circuit, the circuit for coil 40 being traced from the left-hand terminal of the coil through wire 42, the lower portion of a resistor R2, as viewed in Fig. 1, to an intermediate adjustable terminal 43, a tuning coil 44 and wire 45 to a junction terminal of the two coils 40 and 41. Similarly, the circuit for the pick-up coil 41 can be traced from the right-hand terminal of the coil through wire 46, top portion of resistor R2 to intermediate terminal 43, coil 44 and wire 45 to the junction terminal of the two pick-up coils. The tuning coil 44 is provided with an adjustable core or otherwise made adjustable to tune the two receiving circuits to resonance of the frequency of the alternating current supplied from the oscillator OS. A capacitor 47 is connected across coil 44 to aid in tuning the associated receiving circuits and to by-pass noise energy of frequency other than that of the test current. By proper positioning of the intermediate terminal 43 along resistor R2, the two receiving circuits are in balance. The connections for the pick-up coils 40 and 41 are such that the electromotive forces induced therein by the testing current flowing in the rails in multiple tend to cause currents to flow in opposite directions through the tuning coil 44, and the two currents cancel as long as the testing current is of equal value in the two rails. The tuning coil 44 is connected across control electrode 36 and cathode 34 of the tube ET by an obvious circuit.

Thus when the locomotive LO is moving over a track in which the rail bonds are in good condition and an approximately equal value of the testing current supplied by the oscillator OS flows in each rail, equal electromotive forces are picked up by the coils 40 and 41 and the voltages applied to coil 44 by the two corresponding receiving circuits will balance out and no control voltage is applied to the control electrode 36 of tube ET.

with the result no shadow angle appears for the corresponding section of the tube.

If a rail joint having a broken rail bond is approached, the current of the oscillator OS will be greater in the rail not having the broken bond, and thus the electromotive forces induced in the coils 40 and 41 will be unequal. A voltage equal to the difference of the two electromotive forces is now developed across the coil 44 and a corresponding voltage is applied to control electrode 36 so that a corresponding shadow angle is displayed in the corresponding section of the tube ET. This means that there is displayed a specific indication at the electron ray tube ET to the operator of the locomotive whenever the locomotive passes over a rail joint having a broken rail bond.

To sum up the operation of the test equipment of Fig. 1, the operator of the locomotive LO sets the oscillator OS into operation to supply testing current to the trolley wire and rails and then runs the locomotive slowly over the mine tracks. Between adjacent hangers and on stretches where the insulators of the hangers are in good condition, no indication is displayed at the indicator tube ET. When the locomotive LO passes a hanger having a short circuited or defective insulator that permits current to leak from the trolley wire into the mine roof, an indication of such condition is displayed in one section of the tube ET. When the locomotive passes a rail joint having a broken rail bond, then an indication of that condition is displayed in the other section of the tube ET. Thus the operator by observing the two shadow angles of the tube ET as the locomotive is operated over the tracks can detect the broken down trolley wire insulators and broken rail bonds.

In Fig. 2 a modification of the portion of the equipment for testing rail bonds is disclosed. A mine locomotive LO is indicated conventionally as traveling over the rails 1a and 1b of the mine track MT, and this locomotive is provided with two pick-up coils 40 and 41 for receiving electromotive forces due to the alternating test current applied to the trolley wire and rails the same as in Fig. 1. The pick-up coils 40 and 41 of Fig. 2 are connected to tuned receiving circuits, the circuit for coil 40 including capacitor 50 and input terminals of a full wave rectifier 51, the output terminals of which rectifier are connected across the lower portion of a resistor R3 and an indicator A. Similarly, the receiving circuit for pick-up coil 41 includes a capacitor 53 and input terminals of a full wave rectifier 54, the output terminals of rectifier 54 being connected across the upper portion of resistor R3 and indicator A. The connections for the output terminals of the rectifiers 51 and 54 are such that current from rectifier 51 tends to flow through the indicator A from right to left and the lower portion of resistor R3, and the current from the rectifier 54 tends to flow through the upper portion of resistor R3 and indicator A from left to right. When equal portions of the alternating test current flow in rails 1a and 1b, the two rectified currents applied to indicator A are equal and opposite and cancel, causing the indicator to display a zero reading. The terminal 52 of the resistor R3 is made adjustable to normally condition the two circuits for the indicator A to give a zero reading. If the locomotive LO of Fig. 2 is moving along the track and a broken rail bond or abnormally high resistance bond is encountered, the test current will be unequal in the two rails, and

the unequal electromotive forces induced in the pick-up coils 40 and 41 will cause a corresponding current to flow in one direction or the other through the indicator A with the result that indicator A will display a corresponding indication. It is obvious from the foregoing that the apparatus of Fig. 2 can be used in the equipment of Fig. 1 for that portion of the test equipment for testing broken rail bonds.

10 It is to be pointed out that for testing rail bonds only the apparatus of Fig. 2 can be arranged for the source of alternating current, such as oscillator OS of Fig. 1, to be connected to a coil mounted above one rail or two coils, one mounted above each rail at the end of the locomotive opposite the position of the pick-up coils 40 and 41 and the test current applied to the rails by electromagnetic induction. The test current then flows in the rails in multiple and returns through 20 the ground due to the distributed rail to ground impedance.

It is also to be observed that with test equipment here disclosed, the locomotive can be provided with a paint or whitewash type of marker 25 under the control of the operator, and the operator can leave a telltale mark on the ties or other portions of the track at locations of faulty trolley wire insulators and rail bonds as an aid to the repair crew.

30 It is apparent that that portion of the equipment for testing the trolley wire insulators can be used alone or that portion for testing the rail bonds can be used alone.

35 Test equipment here disclosed has the advantages that the trolley wire insulators and rail bonds can be tested accurately and with dispatch.

Although I have herein shown and described only certain forms of equipment for testing trolley wire insulators and rail bonds of electric railways embodying my invention, it is understood 40 that various changes and modifications may be made therein within the scope of the appended claims without departing from the spirit and scope of my invention.

45 Having thus described my invention, what I claim is:

1. In test equipment for an electric railway, the combination comprising, a source of alternating current of relatively high frequency mounted on 50 a vehicle of said railway and having connections to the propulsion conductor and to the track rails to cause alternating current to flow in said propulsion conductor from said vehicle and return through the track rails in multiple, a pair of receiving circuits on said vehicle each including a pick-up coil, said pick-up coils mounted one over each track rail, said pick-up coils alike and disposed for substantially like inductive relationship to the respective rails, a tuning coil on 55 said vehicle, said receiving circuit differentially connected across said tuning coil to create a voltage across the tuning coil when unequal values of said alternating current flows in the track rails, and an indicator connected across said tuning coil responsive to such voltage.

60 2. In test equipment for an electric railway having a propulsion circuit which includes a trolley wire and bonded track rails, the combination comprising, a source of alternating current mounted on a vehicle of said railway coupled to the trolley wire and the track rails of the propulsion circuit of said railway to cause substantially equal values of alternating current to flow 70 in the track rails under normal condition of the rail bonds, a pair of pick-up coils on said vehicle
